UNITED STATES PATENT OFFICE

ROCKEL ALEXANDER FRITSCH, OF MAZATLAN, MEXICO, ASSIGNOR TO JOHN LAWRIE,
OF CHICAGO, ILLINOIS

FOUNTAIN PEN

Application filed March 14, 1927. Serial No. 175,828.

This invention aims to provide a self-filling fountain pen so organized and constructed as to be readily filled in a simple, positive manner by one hand and characterized by large 5 ink capacity in comparison with its bulk. Other objects and advantages reside in certain novel features of the construction, arrangement and combination of parts which will be hereinafter more fully described, in 10 connection with the accompanying drawings forming a part of this specification, wherein like reference numerals refer to the same parts throughout and wherein,

Fig. 1 is a longitudinal central section illustrating a preferred embodiment of my invention;

Fig. 2 is an enlarged detail view of the lower end of the construction shown by Fig. 1 with the piston pushed back as in the filling 20 operation;

Figs. 3 and 4 illustrate modified lower end constructions, corresponding to Fig. 2; and

Fig. 5 is a detail of a modified butt end construction.

25 It will be understood in the following description and claims that the terms "upper", "lower" and the like are used with reference to the normal position of the pen when writing, the lower end, also referred to as the 30 writing end, being that which carries the pen point.

The term "solidly closed" as used in this 35 specification means "permanently ink-tight with no openings or packed piston orifices through which ink leaks might develop", and while solidly closed barrels have been used heretofore in fountain pens, such as the dropper filled pens, I believe this to be the 40 first multi-stroke self-filling fountain pen to incorporate such a permanently ink-tight barrel.

The form of my pen shown by Figs. 1 and 2 comprises a barrel 1 whose only opening is at the lower end, said barrel being fitted with 45 an interior axial tube 2 of relatively small diameter, open only at the top and bottom, extending substantially its entire length, which tube is secured to the center of the upper end of said barrel. The lower end of 50 the barrel is closed, forming an ink reservoir,

by a reciprocable tubular piston 3, the travel of which is guided and outwardly limited by a bushing 4 which also serves as a finishing tip for the lower end of the barrel.

Externally the piston 3 consists of three 55 mutually rigid cylindrical portions of successively diminishing diameter, having a common axis. The top section 5, having the greatest diameter, makes a sliding liquid-tight fit with the interior of the lower end 60 of the barrel, and terminates forwardly in a shoulder 6. The middle section terminates in a shoulder 7, which, when the piston is extended to the normal writing position of Fig. 1, abuts against an inner shoulder of the bushing 4. The upper and middle sections, which 65 are of approximately equal length, remain at all times within the barrel, while the lowest section, which makes an easy sliding fit within the bushing 4, is about as long as the other 70 two combined, and protrudes, when extended, beyond the bushing a distance substantially equal to the reciprocation of the piston.

The interior of the tubular piston 3 is of 75 large diameter within the enlarged portion 5, thus only slightly diminishing the capacity of the ink reservoir, and is reduced by a tapering shoulder 8 to a passage 9 of smaller uniform diameter through the two lower portions. A plug 10 permanently closes the lower 80 end of the piston 3. This plug is suitably shaped, as at 11, to support a pen point 12, held in position in the usual manner. A central passage 13, hole 15 and ducts 16 provide 85 an ink channel for feeding and for filling. This passage 13 is of proper diameter and shape to permit the tube 2 to slide freely therein with a substantially ink- and air-tight fit, and is tapered at its upper end to facilitate the entrance of the lower end 17, also 90 tapered, of said tube. When the piston 3 is in extended position a narrow space 18, just sufficient for the feed of ink from the lower end of the reservoir to the pen point, is left between the end 17 and the entrance to the 95 passage 13.

The middle portion of the piston, the periphery of which, by reason of its reduced diameter, is spaced from the inside of the barrel, is surrounded by a coiled tension 100

spring 21, the ends 22 and 23 of which are respectively inwardly and outwardly turned into suitable notches in the piston and in the barrel. To equalize air pressure in the spring space when the piston is reciprocated the fit between the piston and the bushing 4 may be a little loose, or this result may be accomplished by a longitudinal groove on either the inner surface of the bushing or the outer surface of the piston.

10 The upper end of the tube 2, which is secured in the upper end of the barrel, may communicate with the ink reservoir by small holes 28, Fig. 1, or by channels 29 within the head of the barrel, Fig. 5.

15 Figs. 3 and 4 show the use of a compression spring instead of a tension spring.

Besides permitting a shorter assembly, the use of a compression instead of a tension 20 spring gives a smoother piston action because such a spring reacts against the entire circumference of the shoulder 31 and flange 32.

Fig. 3 illustrates a modification of the construction of Fig. 2, wherein the barrel bushing 40 is cylindrical and of the same external diameter as the barrel, and the passage through the piston is enlarged, forming an additional ink chamber 41, having a 25 collar 42 at the top within which the lower end of the tube 2 slides, and closed at the bottom by a pen-holder block 43. The collar tapers upwardly and outwardly to meet the enlarged upper sleeve of the piston, the inner taper being steepened as shown at 30 44 to guide the lower end 17 of the tube 2 into said opening. In this modification the upper end of the pen-holding block 43, in combination with the pen point, forms the bottom of the chamber 41, while the lower end constitutes the usual pen-supporting tongue. Ink 35 channels 45 in one side of the block lead from the central passage to the pen. The head 46 of the block is inclined toward the channel side to carry the last drop of ink to the pen point.

Fig. 4 illustrates a simplified piston construction comprising an integral flanged lower portion 51 internally threaded at its upper 50 end and an upper enlarged portion 52 connected therewith by an externally threaded nipple 50.

It is to be understood that such features as are not specifically described in connection 55 with each of my various modifications are similar in construction to the corresponding elements in figures which are completely described and that the characteristic features of the several embodiments, where not inconsistent, may be used together in various combinations other than those herein shown and described.

The various component elements of the 60 barrel and of the piston may be assembled

in any suitable manner, for instance, by screw threads or force fits.

To fill my improved pen the point is submerged in ink against an unyielding surface, and the barrel alternately pushed down by hand and allowed to rise by the action of the spring. The down stroke reduces the size of the ink chamber, forcing air out through the holes 28, or passages 29, the tube 2 and the piston passages. The up stroke sucks ink up through the same course. This ink falls into the bottom of the reservoir, whence it cannot escape, except in minute quantities at the beginning of the succeeding down stroke, for the reason that the bottom flow opening, is 70 narrowly restricted, and moreover this opening is closed by the beginning of the down stroke. Completion of filling will be indicated by cessation of bubbles from the point, and by increasing resistance to the down stroke caused by expulsion of ink instead of air. It will be seen, however, that no injury to the open pen can result from unnecessary continuation of the pumping process, since 75 this will only cause a continued circulation of ink.

When due to dryness at the pen point or other causes, the flow of ink does not readily begin, it may be started by pushing the barrel slightly downward on the piston.

It will be seen from the foregoing that I have invented a pen of simple and durable construction, reliable and efficient in operation, easily and cheaply manufactured, and leak proof by reason of having no openings 100 in the top or sides of the barrel. Maximum ink capacity in relation to the size of the pen is secured by the absence of waste space in the ink chamber, since there is no sack, since the tube 2 is filled when the chamber is full, and since the piston is hollow.

Having described certain preferred embodiments of my invention without restricting myself thereto, what I claim is:

1. In a fountain pen, in combination, a rigid reservoir, a piston in the writing end of said reservoir, said piston being adapted to be reciprocated therein by alternate manual and spring action applied at said writing end for filling said pen.

2. In a self-filling fountain pen of the piston type, a barrel solidly closed at one end, said barrel having a relatively small axial tube centrally secured to said closed end, said tube provided with orifices at each end only, said tube being adapted to carry alternate outflow and inflow of the contents of said barrel.

3. In a fountain pen, in combination, a barrel, a permanent closure at the upper end of said barrel, a restrictedly reciprocable closing member at the lower end of said barrel, a relatively small interior tube extending substantially from end to end of said barrel, said reciprocable closing member hav-

- ing a passage therein, a restricted opening between the interior of said barrel and said passage when said reciprocable closing member is in extended position, said opening being so placed as to be closed by the first part of the inward reciprocation of said reciprocable closing member, the inner end of said passage being adapted to register with and slidably fit the lower end of said interior tube. 5
4. In a fountain pen, in combination, a barrel open only at the writing end, a piston in said writing end and adapted to be actuated from said writing end, said piston being adapted for reciprocation therein for filling said pen. 10
5. In a self-filling fountain pen having a piston, a barrel solidly closed at one end, said barrel having a relatively small longitudinal tube coacting with said piston secured to said closed end, said tube provided with orifices in upper and lower parts, said tube being adapted to carry alternate outflow and inflow of the contents of said barrel. 15
6. A fountain pen including, in combination, an ink reservoir composed of a barrel and a combined piston and feed assembly in the writing end of said barrel, a tube within said reservoir, said tube providing an ink and air passage between the upper end of said reservoir and said combined piston and feed assembly. 20
7. In combination, in a self-filling fountain pen, a cylindrical casing, a point-carrying feed assembly constituting a piston closing one end of said casing and reciprocable therein, said casing end said piston composing an ink reservoir, a channel between the ends of said reservoir, said channel permanently opened in its upper and lower parts, said channel being adapted for egress of air and/or ink from and ingress of ink to said reservoir. 25
8. In a fountain pen, in combination, a tubular ink reservoir, a permanent closure at the upper end of said reservoir, a restrictedly reciprocable filling and feed member at the lower end of said reservoir, a relatively small interior tube extending substantially the length of said reservoir, said reciprocable filling and feed member having a passage therein, a restricted feed space between the interior of said reservoir and said passage when said reciprocable filling and feed member is in extended position, said feed space being so arranged as to be closed by the first portion of the inward movement of said reciprocable filling and feed member, the inner end of said passage being adapted to 30 envelope and slidably fit the lower end of said interior tube. 35
9. In a fountain pen, in combination, a tubular reservoir closed at its upper end, a tubular feeding and filling piston comprising its lower end, an ink distributing pen 40
- point support fixed to the lower end of said piston, an inner ink and air carrying tube open in its upper and lower portions, said tube having its upper part fixed to the inner upper portion of said tubular reservoir and its lower portion adapted for insertion into said tubular piston thereby to trap ink in said reservoir. 70
10. In a fountain pen of the self-filling style, in combination, a writing member, a reservoir adapted to supply ink thereto, said reservoir comprising a rigid cylinder closed except at the lower end, a movable piston within said reservoir, said piston adapted to be actuated from said lower end to expel air from and take ink into said reservoir, and only means of ingress and egress of ink and/or air through said lower end, and an inner tubular passage between the lower and the upper portions of said reservoir. 75
11. In a fountain pen with a filling arrangement, a rigid reservoir solidly closed except at the lower end, an ink passage member operable through said lower end, a piston slidably movable within the lower portion of said reservoir, said piston being connected to said ink passage member, and means for the passage of air through said lower end. 80
12. In a fountain pen with a filling arrangement, in combination, a rigid reservoir barrel solidly closed except at the lower end, an orificed piston operable within said reservoir barrel and bounding the lower end of said reservoir, an operating extension to said piston extending outwardly through the lower end of said reservoir barrel, and means for ingress and egress of ink and/or air through said reservoir barrel lower end and said piston orifice. 85
13. In a fountain pen with a filling arrangement, in combination, a rigid reservoir barrel solidly closed except at the lower end, and a filling piston in said lower end defining the lower end of the reservoir and having its only operating projection extending downwardly through the lower end of said reservoir barrel. 100
14. A fountain pen comprising, in combination, a substantially rigid cylindrical reservoir solidly closed at the sides and upper end and having a single opening at the lower end thereof, a piston-type filling device extending through said opening and into the lower portion of said reservoir and slidably operable through said opening, and a point-carrier and spring return means for actuating said filling device. 110
15. In a fountain pen, in combination, a substantially rigid reservoir solidly closed except at the writing end, a piston within said reservoir and reciprocably operable through said writing end, said piston having a passage therethrough, and means tending to return said piston to its normal outwardly extended position on inward movement of 120
16. In a fountain pen, in combination, a substantially rigid reservoir solidly closed except at the writing end, a piston within said reservoir and reciprocably operable through said writing end, said piston having a passage therethrough, and means tending to return said piston to its normal outwardly extended position on inward movement of 130

said piston so that by alternate inward and automatic outward impulsion air may be expelled from, and ink drawn into, said reservoir.

16. A fountain pen comprising, in combination, a rigid cylindrical reservoir having an opening only in the point end, a piston type filling device reciprocable operable through said opening, and a point-carrier outside said reservoir and attached to the outer end of said filling device.

17. In a self-filling fountain pen, in combination, a barrel, a piston mounted for reciprocation in the lower end of said barrel, said piston having an ink and/or air carrying channel therein, an ink and/or air carrying tube in said barrel adapted to enter said channel, and an enlargement at the upper end of said channel to facilitate entrance of said tube thereinto.

18. In a self-filling fountain pen, in combination, a rigid reservoir solidly closed except at the writing end and a filling device operable through the writing end of said reservoir.

19. In a self-filling type of fountain pen, in combination, a rigid cylinder forming an ink reservoir solidly closed except at its lower end, a writing element slidably mounted in the lower end of said reservoir, a piston connected to said writing element, said piston arranged for upward and downward movement in said reservoir for the expulsion of air and intake of ink through said writing element, said writing element forming the sole stem for operating said piston in one direction, and means for returning the piston in the other direction.

20. In a self-filling type of fountain pen, in combination, a substantially rigid reservoir, a filling device reciprocable within said reservoir and operable through the point end thereof for expulsion of air and intake of ink through said point end, and means for storing energy during reciprocation of said device in one direction, said reciprocation being adapted to be accomplished by alternate application of external force and release of energy stored.

21. In a self-filling fountain pen of the piston type; a reservoir, said reservoir being defined by two telescoping members the outer of said members being solidly closed at its outer end and comprising the butt end of the pen; a tube carried by said closed outer end and extending toward the other end of said outer member, said tube being in communication with the interior of said outer member adjacent said closed outer end; a writing point carried by the outer end of the inner of said telescoping members; the outer end of the inner of said telescoping member having a channel therein communicating with said writing point; an annular wall lying between said writing point and the inner end of the inner

of said telescoping members; said tube and inner surface of said annular wall slidably cooperating during at least the major part of the filling operation to trap ink in the writing end of said reservoir, said tube communicating at its outer end with said channel; said filling operation being effected by relative motion of said telescoping members; said tube being formed to open communication past said wall from the writing end of said reservoir to said channel in the writing position of the pen mechanism.

22. In a self-filling fountain pen of the piston type; a reservoir; said reservoir being defined by two telescoping members the outer of said members being entirely closed at its outer end and comprising the butt end of the pen, said outer member being imperforate and extending substantially to the outer extremity of said inner member; a tube carried by said closed outer end and extending toward the other end of said outer member, said tube being in communication with the interior of said outer member adjacent said closed outer end; a writing point carried by the outer end of the inner of said telescoping members; the outer end of the inner of said telescoping members having a channel therein communicating with said writing point; an annular wall lying between said writing point and the inner end of the inner of said telescoping members; said tube and inner surface of said annular wall slidably cooperating during at least the major part of the filling operation to trap ink in the writing end of said reservoir, said tube communicating at its outer end with said channel; said filling operation being effected by relative motion of said telescoping members; said tube being formed to open communication past said wall from the writing end of said reservoir to said channel in the writing position of the pen mechanism.

23. In a self-filling fountain pen of the piston type; a barrel forming an ink reservoir; a relatively movable orifice defining wall and a member defining a channel at the writing end of said ink reservoir; a writing point in communication with said channel, a tube carried by said reservoir barrel, and extending to the writing end of said reservoir, and communicating at its outer end with said channel, and slidably cooperating with said orifice defining wall during at least the major part of the filling operation to trap ink in the writing end of said reservoir; the parts being arranged so that said tube is moved outwardly with respect to said orifice during the operation of filling said pen; said tube being formed to open communication past said orifice defining wall from the writing end of said reservoir to said channel in the writing position of the pen mechanism.

24. In a self-filling fountain pen of the piston type; an ink feeding and trapping mech-

anism including an apertured wall at the writing end of the ink reservoir barrel and movable relative thereto, a tube positioned for sliding cooperation with said apertured wall during at least the major part of the filling operation, which is effected by relative movement of said barrel and wall, to trap ink in the writing end of said reservoir, said tube being formed to open communication past said wall from the writing end of said reservoir in the writing position of the pen mechanism.

25. In a fountain pen of the self-filling style, in combination, a writing member, a reservoir adapted to supply ink thereto, said reservoir comprising a rigid cylinder closed except at the lower end and having its imperforate side walls extending to a point on the assembled pen beyond the point normally grasped in holding the pen for writing, a movable piston within said reservoir, said piston adapted to be actuated from said lower end to expel air from and take ink into said reservoir, an only means of ingress and egress of ink and/or air through said lower end, and an inner tube having a passage between the lower and upper portions of said reservoir.

26. In a fountain pen, in combination, a barrel open only at the writing end and having its imperforate side walls extending to a point on the assembled pen beyond the point normally grasped in holding the pen for writing, a piston in said writing end and adapted to be actuated from said writing end, said piston being adapted for reciprocation therein for filling said pen.

In testimony whereof, I have signed my name to this specification.

CERTIFICATE OF CORRECTION.

Patent No. 1,733,342.

Granted October 29, 1929, to

ROCKEL ALEXANDER FRITSCH.

It is hereby certified that error appears in the printed specification of the above numbered patent requiring correction as follows: Page 3, line 37, claim 7, for the word "end" read "and"; same page, line 81, claim 10, for the word "and" second occurrence, read "an"; and that the said Letters Patent should be read with these corrections therein that the same may conform to the record of the case in the Patent Office.

Signed and sealed this 12th day of November, A. D. 1929.

(Seal)

M. J. Moore,
Acting Commissioner of Patents.
